UNITED STATES PATENT OFFICE.

JOSEPH PRUDHOMME, OF PORTLAND, OREGON.

FOIL-EMBOSSING MACHINE.

Application filed May 23, 1922. Serial No. 563,169.

To all whom it may concern:

Be it hereby known that I, JOSEPH PRUDHOMME, a citizen of the United States, and a resident of Portland, in the county of Multnomah and State of Oregon, have invented a new and useful Foil-Embossing Machine, of which the following is a specification.

This invention relates more particularly to printing machines known as web presses which are adapted to print on foils of tin, lead, aluminum, etc.

The object of my invention is to provide an exceedingly simple, efficient and inexpensive device which will emboss foil as it is drawn from the roll to be printed, and to so construct the device that the usual expensive embossing rolls may be dispensed with and thereby permit numerous changes in the design of the embossing without the entailment of any great expense.

A further object is to improve the quality of the work and to make same more uniform throughout.

I accomplish these results in the manner set forth in the following specification and illustrated in the accompanying drawing, in which:

Figure 1 is a right side elevation showing the device attached to the foil receiving end of a press, the press being shown in dotted lines. Figure 2 is a front elevation of Figure 1 of which Figure 3 is a plan. Figure 4 is a left side elevation showing the gearing. Figure 5 is an enlarged detail showing the special embossing rolls.

Similar numbers of reference refer to the same or similar parts throughout the several views.

Referring in detail to the drawing, I have constructed my device as an attachment for the usual web press 10 having feed rolls 11 for drawing the foil 12 into the press. This foil 12, it will be understood, is now embossed on a separate machine and then re-rolled before running through the printing press.

Referring more particularly to my device I have constructed same of a pair of side frames 13 and 14 which have inturned base members 15 which are secured to the press 10 by the bolts 16. Journaling in the bearings 17 on the frames 13 and 14 is the main shaft 18, one end of which is near the frame 14 and has secured on same a bevel gear 19 which meshes with and is driven by the

bevel gear 20 on the shaft 21 which journals in the standard 22 on the press 10. On the opposite end of the shaft 18 is secured the spur pinion 23 which meshes with and drives the spur gear 24 on the countershaft 25, which also journals in the frames 13 and 14. The gear 26 on the counter shaft 25 drives the embossing roller shaft 27 through the gear 28 on which shaft is secured an arbor or cylinder 29, on each end of which is placed a sleeve 30 which is beveled at the face 31 to hold an electrotype embossing plate 32 bearing on its surface 33 the desired embossing form. The screws 34 clamp the sleeves 30 tightly to the cylindrical electroplate 32. On the stationary shaft 35, which is held by the frames 13 and 14, are placed the arms 36 which are held against movement toward the frames by the pinned collars 37.

Journaling in the arm 36 is the shaft 38 on which is placed the arbor 39 upon which is secured a rubber roller 40 which is therefore able to swing on the center of the shaft 38 within certain limits.

The ends 41 of the arms 36 are slotted to receive the eccentrics 42 on the eccentric shaft 43 which journals in the frames 13 and 14. The eccentric operating lever 44 and the collar 45 are pinned on opposite sides of the journal for the shaft 43 and hold same in place. The plates 46 separate the under sides of the eccentric 42 from the lower sides of the slotted ends 41 and the screws 47 regulate the impression on the roller 40 upon the electrotype cylinder 42, the pressure being greatest when the lever 44 is approximately in a vertical position as shown in Fig. 1.

A foil roll rack is also used and consists of a pair of vertical rods 48 upon whose upper ends is mounted the foil roll spool shaft 49 which is braced from the members 13 and 14 by the rods 50. Extensions 51 of the rods 48 carry an idler spool 52.

The operation of my device is as follows: The roll 53 of the foil 12 is placed on the shaft 49 and the foil carried over and under the rubber roller 40 and downwardly against the member 32 while the lever 44 is raised, which separates the rolls 32 and 40 then sags under the roll 53, after which the foil is carried over the roller 52 to the rolls 11 of the press 10.

It will be seen that the rolls 11 being driven by the press will draw the foil as re-

quired, and since the tensile strength of the foil is small no tearing is experienced since all that the roll 11 must do is to pull up part of the slack 12^A from the foil 12.

5 While the gearing in my device is adapted to drive the rolls at the same speed that the foil is used by the press it is practically impossible to prevent a gradual loss or gain in the slack 12^A. However, the amount of slack 10 12^A can be increased or decreased at will by the operator who raises the lever 44 and retards or accelerates the rotation of the roll 53 momentarily, after which the lever 44 is again pressed down.

15 It will be understood that under the present methods a steel embossing roll is engraved and hardened and sufficient pressure is applied to cause a duplicate of the engraving to be formed in a soft steel companion roll. The cost of the original steel 20 engraving is very high and requires a correct adjustment and impression to make the two rolls register properly.

It is evident that in my device the electro- 25 type can be made flat and rolled to fit a round arbor, or can be made cylindrical without any seam in its circumference.

What I claim as new is:

1. The combination of a cylindrical electro- 30 type driven in unison with a printing press with an adjustable roller adapted to press foil against said electrotype and to be frictionally driven by said electrotype.

2. The combination of a printing press 35 with a power driven cylindrical electrotype, a rubber roller adjustably and rotatably mounted over said cylinder, gearing for driving said cylinder and roll in unison with the feed rolls of said press, and a rack

adapted to hold a roll of foil and to allow 40 said foil to pass over said rubber roll then between said rubber roll and electrotype and then to said press feed rolls.

3. A printing press in combination with a foil embossing device arranged to draw 45 said foil from a roll, emboss same and then permit it to fall loosely in front of the feed roll of said press, said embossing device consisting of a pair of frames secured to said press, a cylindrical electrotype journaling in said frame, means for rotating said cylinder in unison with the feed of said press, a rubber roller above said electro, 50 swinging arm members attached to said frames and supporting said rubber roll, a 55 pair of eccentrics within slots in the ends of said arms, a shaft journaling in said frames and carrying said eccentrics, a lever for rocking said shaft, and a foil roll carrying rack attached to said frames.

4. A printing press in combination with a foil embossing device consisting of a foil 60 rack and pair of embossing rolls adapted to draw said foil from the rack and to emboss same, an idler roller means adapted to carry the embossed foil loosely to the receiving end of said printing press.

5. The combination of a press feed mechanism with an embossing device consisting of a foil roll rack, embossing rolls driven 70 from said press and drawing said foil from said roll, and conveyor means for loosely supporting said foil until it reaches said press in a manner that only enough tension 75 is exerted by the press feed rolls to pick up some of the slack in said foil.

JOSEPH PRUDHOMME.
